ANTIVIBRATION GEAR DRIVE

Frederick R. Gruner, West Allis, Wis., assignor
to Allis-Chalmers Manufacturing Company,
Milwaukee, Wis., a corporation of Delaware

Application December 23, 1949, Serial No. 134,685

6 Claims. (Cl. 74—665)

1

This invention relates to antivibration toothed gear drives, particularly adapted for rotating a kiln shell. A principal object of the invention is the provision of new and improved toothed gear drives of these types.

The adoption of modern increased kiln dimensions and greater rotational kiln speeds presents serious vibrational problems which may become destructive under certain circumstances. An illustration of the vibrational difficulties encountered with modern kiln units may be shown by way of example only, using a kiln rotating at a critical speed (herein defined as that speed at which resonance occurs) of one revolution per minute and driven with a main gear having 200 teeth engagements per minute. Since the ratio of the teeth in the main gear to the teeth in the driving pinion is usually large, in the order of ten to one, the variation in torque transmission becomes appreciable. Should the natural vibrational frequency of the kiln and the drive approach 200 vibrations per minute, the vibrational amplitudes of the system will become dangerously large. This excessive vibratory effect has been somewhat reduced in the adoption of a dual drive system. In a dual pinion drive, finer pitch gears may be used instead of the coarse pitch gears in a single pinion drive, to result in smoother torque transmission. Resonance nevertheless may still occur and hence it is a further object of this invention to provide a positive means for obviating this undesirable excessive vibrational effect.

Other objects will appear hereinafter as the description of the invention proceeds.

The novel features of the invention and how the objects are attained will appear from this specification and the accompanying drawing showing several embodiments of the invention and forming a part of this application, and all of these novel features are intended to be pointed out in the claims.

In the drawing:

Fig. 1 is a side elevational view partly in section showing one torque transmitting drive;

Fig. 2 is an enlarged fragmentary end view of 45 gearing embodying my invention;

Fig. 3 is a graphical showing comparing the vibrational waves set up in rotating a kiln shell, when using a dual pinion drive according to my invention, and a conventional single pinion drive;

Fig. 4 is a diagrammatic illustration of a four pinion drive; and

Fig. 5 is a graphical showing of the vibrational waves produced in a drive as illustrated in Fig. 4.

2

An embodiment of the invention is herein shown in Figs. 2, 3 as applied to a dual pinion drive transmission designated by gear means such as driving pinions 5, 6, for rotating a kiln shell. However, any number of pinions as may be practical for operation may be used in the practice of my invention, not only adapted for rotating a kiln shell, but for rotating any elongated member supported for rotation about its longitudinal axis.

Fig. 1 illustrates a suitable drive or torque transmitting unit for rotating one of the driving pinions, incorporated in the teaching of my invention, in this instance pinion 6, and is representative of similar independent drive units for respectively driving the other or remaining driving pinions.

The torque transmitting unit comprises a bearing support, herein shown as a double bearing pedestal 7 for rotatably receiving a pinion shaft 8a for driving the driving pinion 6, a gear reducer unit 9 and a motor means such as a motor 11a. The pinion shaft 8a is preferably connected by means of a torsionally flexible coupling 12, to a low speed shaft 13 of the gear reducer 9; and a high speed shaft 14 of the gear reducer may be driven by a pulley 16 directly connected with a V-belt drive 19, or other suitable driving means, from a pulley 17 secured to the armature shaft 20 of the motor 11a. One end of the high speed shaft 14 is supported as herein shown on a bearing pedestal 18.

The other driving pinion 5 of the dual pinion drive is driven by a shaft 8b through another torque transmitting means as hereinbefore described including a motor 11b (not shown) corresponding to the motor 11a. The motors 11a and 11b are preferably of the type having a drooping operating characteristic, more fully described in the operation of my invention.

Supported for rotation about its longitudinal axis by any suitable means (not shown) is a kiln shell 21 provided with a main or externally toothed driven gear 23 secured about its outer periphery. The pinion drive gears 5, 6 and the main gear 23 may be of the spur type, but helical, herringbone or any other known suitable gears or gear combinations may be used. Spur gears are herein shown to more clearly present the objects of my invention, since the vibrational effects created in meshing a spur gear having a large number of teeth with a spur gear having a relatively small number of teeth are more pronounced than would be obtained between comparable helical or herringbone gears, due to 55 a greater number of teeth in contact at any one

time with the latter two gears than with spur gears.

Fig. 2 clearly shows one of the principal features of my invention as applied to a dual pinion drive transmission. The driving pinions 5, 6, mounted on the shafts 8b and 8a, respectively, are circumferentially spaced about the main gear 23, and meshingly engageable therewith for rotating the kiln shell 21 about its longitudinal axis. An angle ω defined by radial lines 24, 25 10 extended from the center of the kiln shell 21 and expressed in degrees by the formula

$$\beta \left(a + \frac{1}{n} \right)$$

5

15

where β is an angle defining the circular tooth pitch of the main gear 23 in degrees, a is any integer within reasonable construction limits, and n is the number of driving pinions, determines the angle the axes of the driving pinions are circumferentially spaced apart with respect to each other. Hence the driving pinions 5, 6 are staggered for engagement with the main gear 23

$$\frac{\beta}{n}$$

degrees or

$$\frac{1}{n}$$

55 circular tooth pitch with respect to each other. A specific example illustrated by Fig. 2 may be as follows: where $\beta=6^\circ$, $a=14$ and $n=2$; hence $\omega=87^\circ$. Obviously a could theoretically equal zero for the operation of my invention, but in practice the space interference of the driving pinions would eliminate such possibility without an axial displacement of at least one of the driving pinions with respect to the other while simultaneously meshed with the main gear. Conversely a could equal twenty-eight or any other large integer but this would present a supporting problem for at least one or both driving pinions. Therefore a is preferably chosen within reasonable practical limits to obtain a desired circumferential separation of the pinions.

50 The operation of my invention may be graphically illustrated by reference to Fig. 3, wherein the vibrations or nonuniform torque transmissions produced by the meshing engagement of the teeth of the main gear 23 with the driving pinions 5, 6, are substantially herein shown as sine waves. The ordinate represents the amplitude of variation in torque transmission produced from engagement of the driving pinions with the main gear, and the abscissa a period of vibration which is directly proportional to the speed of rotation of the kiln 21.

55 Sine wave 26 is representative of the vibration created with a single driving pinion (not shown), and sine waves 27, 28 are representative of the vibrations created in the adoption of the dual pinion drive transmission herein illustrated. By using the dual pinion drive the torque input per drive is reduced to fifty percent of the torque input required to rotate the kiln when a single pinion drive is used, and hence the amplitude of vibration is accordingly reduced fifty percent.

60 As the driving pinions 5, 6 engage with the main gear 23 for rotation thereof as taught by my invention, each driving pinion will produce the respective sine waves 27, 28 180 degrees out of phase with each other, due to the staggered

65 circumferential spacing of the driving pinions with the main gear. Hence the sine wave 27 cancels the sine wave 28, or conversely, the sine wave 28 cancels the sine wave 27.

70 Fig. 4 shows another embodiment of my invention adopting more than one pair of driving pinions and as herein shown as two pairs, designated by reference characters 30, 31 and 32, 33. The driving pinions 30, 31, 32, 33 may be circumferentially spaced for engagement with a main gear 23a ω' degrees, as expressed by the formula

$$\beta \left(a + \frac{1}{n} \right)$$

75 (where β is the circular tooth pitch in degrees of the main gear 23a) described and explained with respect to the preferred embodiment illustrated in Figs. 2 and 3, and need not be further enlarged upon.

80 Sine waves 35, 36, 37, 38, respectively, represent the vibrational effects created by the engagement of the driving pinions 30, 31, 32, 33 with the main gear 23a. With the adoption of four driving pinions the torque input per drive is reduced to twenty-five percent of the torque input required to rotate the kiln when a single pinion drive is used, and hence the amplitudes of vibration are accordingly reduced to twenty-five percent. This is clearly seen in comparing the vibrational amplitudes of the sine wave 26 with the sine waves 35, 36, 37, 38. Since the driving pinions 30, 31, 32, 33 are staggered

$$\frac{\beta}{n}$$

85 with respect to each other, it is evident from Fig. 5 that two of the driving pinions are 180 degrees out of phase with the other two driving pinions. As herein shown the sine wave 35, or driving pinion 30, is 180 degrees out of phase with the sine wave 37, or driving pinion 32, and the sine wave 36, or driving pinion 31, is 180 degrees out of phase with the sine wave 38, or driving pinion 33, therefore resulting in a zero torque variation as designated by a straight line resultant 39. Although this hereinabove out of phase sine wave relationship is preferable in the adoption of two or more pairs of driving pinions, a zero torque variation can also be effected by placing one-half of the pinions, in this instance 30, 31, in phase or circumferentially arranged β degrees with respect to each other, and staggering this half of the driving pinions for engagement with the main gear 23a, one-half a circular tooth pitch with respect to the other half of the driving pinions 32, 33, where the driving pinions 32, 33 are circumferentially arranged β degrees with respect to each other. 90 Since the driving pinions 30, 31 are in phase with each other as are pinions 32, 33, the vibrational effects produced by each one-half of the total driving pinions during operation may be represented by the sine waves 27, 28, respectively, of Fig. 3. That is to say, the sine waves resulting from the in phase coaction of the driving pinions 30, 31 with the main gear 23a are additive and their resultant sum is equal to a sine wave produced by one driving pinion such as 5 of the dual drive system. Similarly the sine waves resulting from the coaction of driving pinions 32, 33 with the main gear 23a are additive and hence equal to a sine wave produced by one driving pinion such as 6 of the dual drive system. 95 Obviously the position of the respective driv-

ing pinions 30, 31, 32, 33 about the main gear is immaterial, provided they are staggered in

$$\frac{\beta}{n}$$

relationship with respect to each other, or one-half of the driving pinions are staggered in

$$\frac{\beta}{2}$$

relationship with respect to the remaining half of the driving pinions. That is to say, a zero variation or a straight line resultant such as 29 or 39 nevertheless results, if, for example, pinion 31 would be positioned for engagement somewhere between driving pinion 30 and driving pinion 33 instead of between driving pinions 30 and 32, as herein shown.

Whenever any odd number of pinions, such as three, five, seven, etc., is used in the combination, the vibrational amplitudes are, respectively, proportionately diminished, but a resultant periodic reduced vibratory wave (not shown) will result, which is obviously not as desirable as a zero variation herein shown as a straight line resultant 29 or 39, as developed when any even number of pinions are meshed with the main gear 23 in accordance with the formula herein previously set forth.

By varying the stiffness of the pinion shafts 8a and 8b or the low speed shaft 13 or both, and/or the flexible coupling 12, it is possible to change the critical speed above or below the maximum operating rotational speed of the kiln 21, to further diminish excessive vibrational amplitudes. In extremely long kilns, usually 300 feet or more, it is therefore preferable to lower the critical speed by interconnecting the pinion shaft 8a (or shaft 8b) and the low speed shaft 13 with a flexible coupling 12 having a very low stiffness.

Antivibrational performance of the transmission drive will be improved by the drooping characteristics of the motors 11a and 11b obtained by compound wound motors in which the series field adds to the shunt field, or any other known suitable type having only fair regulation, capable of alternately equally sharing the work required to drive the kiln, that is to say, as one of the motors, for example 11a, slows down because of a heavy increase in load, the other motor 11b will speed up until it assumes part of the burden of motor 11a, at which time it will slow down and motor 11a will again speed up. This fluctuation continues as long as the kiln is being rotated, and hence by suitable design of motor characteristics 55 the load distribution on the driving motors can be made substantially equal.

From the foregoing it will be apparent to those skilled in the art that the illustrated embodiments of the invention provide new and improved antivibration gear drive systems for rotary kilns and the like, and accordingly accomplish the objects of the invention. On the other hand, it will also be obvious to those skilled in the art that the illustrated embodiments of the invention may be 65 variously changed and modified, or features thereof, singly or collectively, embodied in other combinations than those illustrated, without departing from the spirit of the invention, or sacrificing all of the advantages thereof, and that 70 accordingly the disclosures herein are illustrative only, and the invention is not limited thereto.

It is claimed and desired to secure by Letters Patent:

1. In an antivibration toothed gear drive, the 75

combination of an externally toothed driven gear rotatable about a first axis, and gear means meshed continually with and simultaneously applying n additive driving forces to said driven gear (where n is an integer greater than one), said gear means comprising a series of n driving pinions mounted in spaced circumferential relation to said driven gear for rotation about respective pinion axes, said pinions being rotatable in fixed out-of-phase relation to each other with reference to lines drawn through said first axis and said respective pinion axes an amount equal to

$$\frac{1}{n}$$

circular tooth pitch of one of said pinions.

2. In an antivibration toothed gear drive, an externally toothed driven gear rotatable about a first axis, and gear means meshed continually with and simultaneously applying n additive driving forces to said driven gear (where n is any even integer), said gear means comprising n driving pinions mounted for rotation about respective pinion axes spaced circumferentially about said driven gear, said pinions being rotatable in fixed out-of-phase relation to each other with reference to lines drawn through said first axis and said respective pinion axes an amount equal to

$$\frac{1}{n}$$

circular tooth pitch of said pinions.

3. In an antivibration toothed gear drive, an externally toothed driven gear rotatable about a first axis, and gear means meshed continually with and simultaneously applying additive driving forces to said driven gear, said gear means comprising two driving pinions mounted for rotation about respective pinion axes spaced circumferentially about said driven gear, said pinions being rotatable in fixed out-of-phase relation to each other with reference to lines drawn through said first axis and said respective pinion axes an amount equal to one-half circular tooth pitch of one of said pinions.

4. In an antivibration toothed gear drive, an externally toothed driven gear rotatable about a first axis, and means meshed continually with and simultaneously applying $2n$ additive driving forces to said driven gear (where n is any even integer), said means comprising n pairs of driving pinions mounted in spaced circumferential relation to said driven gear for rotation about respective pinion axes, the pinions of each pair being rotatable in fixed in-phase relation to each other with reference to lines drawn through said first axis and said pinion axes of said each pair, and the pinions of one pair being rotatable in fixed out-of-phase relation with the pinions of another pair with reference to lines drawn through said first axis and said pinion axes of said one and another pairs an amount equal to

$$\frac{1}{n}$$

circular tooth pitch of one of said pinions.

5. In an antivibration toothed gear drive, an externally toothed driven gear rotatable about a first axis, and means meshed continually with and simultaneously applying additive driving forces to said driven gear, said means comprising n equal sets of gears (where n is an integer greater than one) having a plurality of driving pinions mounted in spaced circumferential relation to said

driven gear for rotation about respective pinion axes, the pinions of each set being rotatable in fixed in-phase relation in each other with reference to lines drawn through said first axis and said pinion axes of said each set, and the pinions of one set being rotatable in fixed out-of-phase relation with the pinions of another set with reference to lines drawn through said first axis and said pinion axes of said one and another sets an amount equal to

$$\frac{1}{n}$$

circular tooth pitch of one of said pinions.

6. In an antivibration toothed spur gear drive, the combination of an externally toothed driven spur gear rotatable about a first axis, gear means meshed continually with and simultaneously applying n additive driving forces to said driven gear (where n is an integer greater than one), said gear means comprising a series of n driving spur pinions mounted in spaced circumferential relation to said driven gear for rotation about respective pinion axes, said pinions being rotatable in fixed out-of-phase relation to each other with reference to lines drawn through said first axis and said respective pinion axes an amount equal to

$$\frac{1}{n}$$

circular tooth pitch of one of said pinions, and individual motor means coupled to each of said pinions in power transmitting relation, each said motor means having a drooping characteristic for so apportioning said driving forces between said pinions that the average value of each said driving force is substantially equal to

$$\frac{1}{n}$$

10 of the sum of said additive driving forces.

FREDERICK R. GRUNER.
